UNITED STATES PATENT OFFICE

100,538

DESIGN FOR AN AIR-CONDITIONING UNIT

Donald D. Boothby, Chicago, Ill., assignor to Air Devices Corporation, Chicago, Ill., a corporation of Delaware

Application May 2, 1936, Serial No. 62,420

Term of patent 14 years

To all whom it may concern:

Be it known that I, Donald D. Boothby, a citizen of the United States, residing at Chicago, in the county of Cook and State of Illinois, have invented a new, original, and ornamental Design for Air-conditioning Units, of which the following is a specification, reference being had to the accompanying drawing, forming part thereof.

Figures 1 and 2 are perspective views, taken looking in opposite directions, of an air-conditioning unit, showing my new design.

Figure 1 shows the top and one end and the side which faces into the room when the unit is in place resting on the sill of a window, and Figure 2 shows the top and the other end and the side which faces outdoors.

I claim:

The ornamental design for an air-conditioning unit, as shown and described.

DONALD D. BOOTHBY.
